Edmund D. Kissling, New York, N. Y.

Application November 8, 1945, Serial No. 123,569

Term of patent 14 years

(Cl. D48—20)

To all whom it may concern:

Be it known that I, Edmund D. Kissling, a citizen of the United States of America, residing at New York, in the county of New York and State of New York, have invented a new, original, and ornamental Design in a Lamp Stand or the like, in which the following is a specification, reference being made to the accompanying drawing, forming a part thereof, in which

Fig. 1 is a front elevational view of a lamp stand or the like, showing my new design.

Fig. 2 is an elevational view of my design shown in Fig. 1, when turned at 45 degrees.

I claim:

The ornamental design for a lamp stand or the like, as shown.

EDMUND D. KISSLING,
